MICHAEL F. DORAN, OF PHILADELPHIA, PENNSYLVANIA.

Letters Patent No. 92,432, dated July 13, 1869.

IMPROVEMENT IN SPOOLS.

The Schedule referred to in these Letters Patent and making part of the same.

To all whom it may concern:

Be it known that I, MICHAEL F. DORAN, of the city and county of Philadelphia, State of Pennsylvania, have invented an Improved Spool; and I do hereby declare the following to be a full, clear, and exact description of the same.

My invention consists of a winding or unwinding-spool, marked substantially as and for the purpose described hereafter.

In order to enable others to make and use my invention, I will now proceed to describe its construction and operation, reference being had to the accompanying drawing, which forms a part of this specification, and in which—

Figure 1 is a side view of my improved spool;

Figure 2, a section on the line 1-2, fig. 1; and

Figure 3, an end view.

The spool consists of the usual spindle, A, and end-pieces B, an opening, a, extending through both, for the reception of the usual spindle.

On the inner side of one or both of the end-pieces or flanges B, are painted, or otherwise marked, stripes or other figures, x, each of these extending across the edge of the end-piece, and terminating (in the present instance) on the outer side of the latter, a short distance below the edge, as seen in fig. 3.

In winding threads, &c., upon, or in unwinding them from a multitude of spools or bobbins of the ordinary description, it is difficult, even for an expert attendant, to perceive, at all times, a cessation of the motion of any one or more of the spools. When, therefore, through any cause, a thread is broken, and the turning of the spool consequently arrested, the fact is liable to escape the immediate notice of the attendant. By striping or otherwise marking the end-pieces of the spool, however, as described above, the breaking of a thread, and consequent cessation of the revolution of the spool, are at once indicated to the attendant, who has to apply the remedy.

I claim as my invention, and desire to secure by Letters Patent—

A winding or unwinding-spool, marked substantially in the manner and for the purpose herein set forth.

In testimony whereof, I have signed my name to this specification, in the presence of two subscribing witnesses.

MICHAEL F. DORAN.
